UNITED STATES PATENT OFFICE

PAUL F. WILLIAMS, OF CHICAGO, ILLINOIS, ASSIGNOR TO G & W ELECTRIC SPECIALTY COMPANY, OF CHICAGO, ILLINOIS, A CORPORATION OF ILLINOIS

POTHEAD

Application filed February 19, 1925. Serial No. 10,210.

This invention relates to potheads.

One object of the invention is to provide a simple, safe, durable and efficient pothead arrangement whereby the portion of cable 5 within the pothead not covered by the sheath is as safe against rupture as the portion covered by the sheath.

Another object is to sheathe a portion of a cable in a pothead and terminate the sheath 10 therein in an improved manner to reduce the tendency to rupture and to offer maximum resistance to rupture.

Another object is to provide a pothead arrangement adapted to meet all of the requirements for successful commercial use.

These and other objects are accomplished by means of the arrangement disclosed on the accompanying sheet of drawings, in which

20 Figure 1 is a vertical longitudinal sectional view through a pothead embodying my invention;

Figure 2 is an elevational view of the same pothead taken at right angles to the pothead 25 as shown in Figure 1, and

Figure 3 is a diagrammatic view showing the direction which the dielectric lines of force are caused to take when the end of the sheath is tapered.

30 The various novel features of the invention will be apparent from the following description and drawings, and will be particularly pointed out in the appended claims.

Referring to the figures of the drawings, 35 it will be noted that I have illustrated my invention in connection with a pothead including a metal cup 10 forming part of a bracket 11, by means of which the pothead may be attached to any suitable supporting 40 structure. Mounted upon the projecting reduced rim portion 12 of the cup is an insulating tube 13 having the usual petticoats 14. The lower end of the tube terminates in a cylindrical portion 15 and extends downwardly within the cup 10. A suitable gasket 45 50 is placed between the cup portion 12 and the cooperating shoulder portion 17 of the tube. The lower end of the cup 10 is tapered downwardly and has connected thereto a wiping sleeve 18, there being a gasket

19 interposed between said parts. A cable 20, including a conductor 21 and insulation 22 wrapped thereabout, extends upwardly through the sleeve 18, cup 10, tube 13 and is electrically and mechanically connected to a 55 cap 23, which fits over the top of the tube 13. A suitable gasket 24 is interposed between the top petticoat of the tube 13 and the cap 23, there being a layer of cement 25 for sealing the cap on said tube. The conductor 21 is electrically connected to a hooded lug 26 mounted over the cap 23 and a cable lug 27 in turn is releasably connected to the hooded lug at 28.

A metal sheath, such for example as a lead 60 sheath 29, surrounds or covers that portion of the cable 20 which extends from the ground and passes through the sleeve 18 and cup 10 and terminates above said cup 10 within the tube 13. A wipe 30 forms a seal 65 between the sheath 29 and the lower tapered portion of the sleeve 18. Liquid dielectric or insulating material is forced into the pothead and fills all space therein, said liquid dielectric material preferably being forced 70 into the pothead through a tube 31 connected to the cup 10, the displaced air being ejected through openings 32 in the cap 23, which 75 openings are normally closed by plugs 33. It will be noted that the cap 23 is provided with considerable space for the storage of dielectric material and, if necessary, an additional amount may be supplied thereto, and also to the tube 13 and cup 10 through connection 31.

80 This pothead is designed particularly for use in connection with high potential current carrying cables. There is a well-established rule that an electric conductor of a given diameter shall be wrapped with a given thickness of a given insulating material to obtain the greatest resistance to breakdown of the insulation. If less insulation is used, the resistance to breakdown usually is decreased and likewise, if an increased amount of insulation is used, 85 especially where the dielectric constant is different, the resistance to breakdown is reduced. An insulated cable passing through a pothead is surrounded by a dielectric insulating material to hermetically seal the cable within the 90 95 100

pothead. As mentioned before, the pothead cup 10 is of metal, and in addition to the insulation around the cable 21 an insulating liquid is forced into the cup and between its walls and the tube and the cable. In so far as the liquid insulating material within the cup is concerned, it may be considered excessive in amount, even to the point of making the total dielectric strength between the cable conductor 21 and the cup 10 weaker than it would be if only the insulating material 22 around the conductor 21 were used. Accordingly the metal sheath 29 is extended completely through the cup 10 and terminates at a point upwardly beyond the rim of said cup. Both the metal cup 10 and the sheath 29 are grounded, and accordingly there is no difference in potential between said cup and sheath. In this way the pothead and/or the sheathing is made more nearly punctureproof.

In order to further safeguard the pothead against puncture, the upper end or member 35 of the sheath is tapered away from the cable, thereby causing the dielectric lines of force at the upper termination of the sheath to be spread out and travel in lines at right angles to the insulation 22, which is wrapped around the cable conductor 21. It is a known fact that the dielectric strength or resistance to breakdown crosswise of wrapped insulation is ten times greater than the dielectric strength lengthwise of said insulation. Accordingly, by tapering the end of the sheath away from the conductor, the lines of force in question are spread out and greater resistance to the dielectric lines of force is presented. In Figure 3 this point is illustrated somewhat diagrammatically, wherein it is noted that the dielectric lines of force 36 are shown as traveling in spread out lines more at right angles with respect to the tapered end of the sheath than dielectric lines of force would travel toward an untapered end of the sheath. The advantage of providing the cable sheathing with the member 35 may be further appreciated when comparing concentration of lines of force at spaced points and the concentration of lines of force due to the same voltage between rounded members. It is a known fact that lines of force will be concentrated at points or sharp edges of members rather than on rounded edges of members when the spacing of said members is equal, and further it is possible to space points at distances from sixteen to twenty times greater than distances between rounded edges of members to cause the same stresses to be concentrated between members and the points for the same voltage. In other words, if the member 35 were not rounded, lines of force would be set up from distances along the cable so far remote from the member 35 that the lines of force will run approximately parallel to the layers of insulation, tending to break down this insulation, whereas by rounding the edge

of the member 35 as illustrated in Figures 1 and 3, lines of force are only effective from such a short distance that they are approximately crosswise of the insulation. As shown in Figure 1, the tapered portion 35 is separate from the main sheath portion 29 and is connected thereto by a wipe joint 37. It will be understood that the relatively soft material, such as lead, used in the main body of the sheath 29 might be tapered away, but it is not as mechanically strong as brass or other conductors which may be used in the tapered away portion 35.

By means of the arrangement hereinabove described a pothead is provided which is adapted to meet all of the requirements for successful commercial use.

I claim:

1. In a device of the class described, the combination of a pothead attaching bracket having a cup, an insulating tube mounted upon and sealed with respect to said cup and being of a smaller internal diameter than said cup, an insulated cable conductor extending through said cup and tube, and a metal sheath covering said cable and entering the bottom of said cup, passing therethrough and extending to a point below the upper edge of said cup and within said tube to decrease the possibility of rupture of the insulation of said cable, said end of the sheath being provided with conducting means supported by the sheath and tapered away from the cable to present the greatest resistance to the dielectric lines of force which tend to rupture the insulation.

2. In a device of the class described, the combination of a pothead attaching bracket having a cup, an insulating tube mounted upon and sealed with respect to said cup and being of a smaller internal diameter than said cup, an insulated cable conductor extending through said cup and tube, a metal sheath covering said cable and entering the bottom of said cup, passing therethrough and extending to a point below the upper edge of said cup and within said tube to decrease the possibility of rupture of the insulation of said cable and pothead, said end of the sheath being provided with conducting means supported by the sheath and tapered away from the cable to present the greatest resistance to the lines of force which tend to rupture the insulation, a metal cap for said tube electrically connected to said conductor, and insulating material within said tube between said sheath and cap and the sheath and cup to prevent the passage of dielectric lines of force therebetween.

3. In a pothead, the combination of a bushing retaining member, an insulating bushing carried by said member, an insulated conductor extending through said retaining member and bushing, sheathing for said insulated conductor, said sheathing extending

an appreciable distance into the insulating bushing and terminating therein, a flared member secured to said end of the sheathing and spaced from said bushing, the termination of the flare of said last named member being a rounded portion to prevent concentration of lines of force tending to disrupt the conductor insulation.

4. In a pothead, the combination of a metallic supporting cup, a hollow insulating bushing supported by and having a portion extending an appreciable distance into said cup, a metallic cap for said bushing, a metallic sheathed insulated conductor extending into said cup and bushing and being electrically connected to said cap, the metallic sheathing of said conductor extending a material distance into said bushing and terminating therein, a metallic member secured to the termination of said sheathing to form a continuation thereof, said metallic member tapering away from said conductor and terminating in a rounded bead at a distance materially above said cup whereby concentration of lines of force tending to disrupt the conductor insulation is prevented, said cup being secured to said sheathing and being free to move with said sheathing and conductor whereby relative movements between the parts of the sheathed conductor tending to disrupt said parts is prevented.

Signed at Chicago, Illinois, this 13th day of February, 1925.

PAUL F. WILLIAMS.
